UNITED STATES PATENT OFFICE.

JOHN HUGHES, OF SOMERVILLE, MASSACHUSETTS, ASSIGNOR TO THE CROSBY STEAM GAGE AND VALVE COMPANY, OF BOSTON, MASSACHUSETTS.

SAFETY-VALVE AND MUFFLER.

SPECIFICATION forming part of Letters Patent No. 631,370, dated August 22, 1899.

Application filed December 24, 1898. Serial No. 700,228. (No model.)

To all whom it may concern:

Be it known that I, JOHN HUGHES, a citizen of the United States, residing at Somerville, in the county of Middlesex and State of Massachusetts, have invented certain new and useful Improvements in Safety-Valves and Mufflers; and I do hereby declare the following to be a full, clear, and exact description of the invention, such as will enable others skilled in the art to which it appertains to make and use the same.

This invention relates to certain improvements in safety-valves and mufflers, and particularly upon the devices shown and described in a patent issued to George H. Crosby, No. 225,801, dated March 23, 1880.

In the annexed drawings, Figure 1 represents the muffled valve in elevation, having a quarter-section removed and in section to show one-half thereof, with all the parts assembled in true relation to each other. Fig. 2 is a transverse section on line xx of Fig. 1. Fig. 3 is a transverse section on yy of Fig. 1. Fig. 4 is a modification of the upper part of Fig. 1 above yy , partly in section.

In the drawings, A is the base of the valve, of which a are the two concentric seats, there being formed within the inner seat a a chamber a' . Leading from this chamber a' are passages a^2 , all of which may be seen in Fig. 2. In the base A is a circular depression a^3 . Mounted on the base A is the valve proper, B, having its concentric seats coincident with the seats of the base A at a .

b is the guide of the valve proper, B, extending downwardly into the chamber a' . (Shown in section in Fig. 2.) At b' the valve rises circumferentially about the lower part of the spring-case C and shuts out the steam from it.

C is the spring-case, attached by proper screw-threads to the base A at c . This case C extends upwardly to the top of the device and through the upper part are small perforations c' to permit any steam which may enter the spring-case to pass outwardly to the open air. (Seen in plan view, Fig. 3, shown through the line yy , Fig. 1.) Within the spring-case C is the spring D, the lower end of which rests upon a circular projection d^3 of the spindle d^2 , the lower end d^4 of the lat-

ter bearing upon the valve proper, B. This spindle d^2 extends upwardly through the valve, having on its upper end screw-threads, upon which is mounted the acorn-shaped nut d^5 , forming a bearing on the underside, against which a lever G impinges. At the upper end of the spring-case C is a hollow spring-bolt d , which extends down to the cap d^6 to compress the spring when required and having upon it the check-nut d' to lock or hold it in place when the spring has been compressed. Attached to the spring-case C at e' is the U-shaped muffling device E, having a series of perforations e , &c.

F is the exterior of the case, corresponding to the case G in the Crosby patent, which surrounds the base A at and below the port a^2 and at f^2 forms a sleeve or gate and is located within the circular channel a^3 . At this point it slides freely around and up and down the case and here performs the same function as the sleeve F does in the Crosby patent. It is formed in two parts, having its joint at f , which is a bolt for securing them together, the upper part extending above and over the muffling device E and is attached to the spring-case C by screw-threads at f^3 . It has in the upper part slots or openings f^5 , through which the steam escapes into the open air after having passed through the perforations e , &c., of the muffling device E. At its union at f it forms a close circumferential contact with the muffling device E, thus compelling all steam which passes through the valve-seats to go through the muffling device, but not so close as to prevent its rotation.

By rotating the case F on the spring-case C at f^3 it rises and falls, so that the lower portion or sleeve f^2 , which surrounds the base A, will modify the area of the ports a^2 , and thus control the volume of the steam which passes into the chamber a' and outwardly through the ports a^2 . The case F has a check-nut f^4 , which locks it in position whenever it has been operated for adjusting the openings of the ports a^2 . Mounted on top of the spring-case C by the hexagonal nut g is a lever G, hinged to the nut at g' . The upper part of lever G impinges on the under side of the acorn-shaped nut d^5 , as before described. In this relation any force exerted upon the

long arm of lever G will lift the spindle d^2 , and thus by releasing the valve proper, B, it will rise under pressure of the steam from the boiler.

5 Fig. 4 is a modification of the muffler at its top, having the lever removed and a small cap H screwed upon the upper part of the spring-case C above the hexagonal nut f^4 of case F.

10 Having described my invention, what I claim is—

1. The combination of a safety-valve provided with one or more steam-escape passages, a^2 , the annular groove, a^3 , the valve-seats, a^4 , and valve B; the adjustable annular exterior case, F, with its bottom edge, f^2 , to fit loosely in the groove, a^3 , the U-shaped muf-

fler, E, connected to the spring-case, C, and the spring-case, C, as and for the purpose described.

2. The combination, in a safety-valve, of an outer case, F, a muffler, E; an inner spring-case, C, these three united as described; the spring, D, the hollow screw-bolt, d , resting on the cap, d^6 , the nuts, d' and g , acorn-shaped nut, d^5 , the lever, G, jointed at g' ; the lock-nut, f^4 , all constructed substantially as and for the purpose described.

In testimony whereof I affix my signature in presence of two witnesses.

JOHN HUGHES.
